UNITED STATES PATENT OFFICE.

JAY F. O'NEAL, OF WATERLOO, IOWA.

TROLLEY SHOE.

Application filed June 2, 1922. Serial No. 565,309.

To all whom it may concern:

Be it known that I, JAY F. O'NEAL, a citizen of the United States, residing at Waterloo, Iowa, have invented certain new and 5 useful Improvements in Trolley Shoes, of which the following is a specification.

My invention pertains to that class of devices which are used in connection with trolley poles to permit the same to have sliding 10 contact with the trolley wire in one direction of travel of the car and rolling contact when travelling in the opposite direction, and among the objects of said invention are to produce an attachment which may be 15 inserted between a standard trolley wheel and harp and perform satisfactorily the service required of such a structure; to provide a structure of the character indicated which will obviate the necessity of using 20 any special form of trolley wheel or harp; to provide a structure for the purpose indicated which can be used along the lines equipped with block signal mechanism; and such further objects, advantages, and capabilities as will later more fully appear.

My invention further resides in the combination, construction, and arrangement of parts illustrated in the accompanying drawing and, while I have shown therein a preferred embodiment of my invention, I desire the same to be understood as illustrative only and not as limiting said invention.

In the drawing annexed hereto and forming a part hereof,

Fig. 1 is a fragmentary elevation of a trolley pole and harp, carrying my new attachment between the harp and the trolley wheel.

Fig. 2 is an end elevation of the structure 40 shown in Fig. 1.

Fig. 3 is a section substantially along the plane indicated by the line 3—3 Fig. 2.

Fig. 4 is a broken plan view of the structure shown in Fig. 1.

Fig. 5 is a sectional elevation substantially along the plane indicated by the line 5—5 Fig. 3.

Referring more in detail to the annexed drawing, numeral 1 designates the trolley 50 pole, 2 an ordinary harp, 3 an ordinary trolley wheel, and 4 denotes generally the attachment constituting the subject matter of my invention. This attachment comprises supporting means consisting essentially of a pair of side plates 5 and a combined weight and wear plate 6, the wear

plate being denoted specifically by the numeral 7 and the remainder of the weight by the numeral 8. The parts 7 and 8 are secured between the side plates 5 by means of 60 bolts 9 and 10. The side plates 5 are provided on their exterior faces, approximately centrally, with trunnions 11 which may be inserted into the bearings 12 of the harp which, as has been indicated above, is an 65 ordinary harp such as is customarily found on trolley poles of the type shown. When the trunnions 11 have been inserted in the bearings 12 weight 8 and wear plate 7 are inserted between the side plates and secured 70 in place by means of bolts 9 and 10. Trolley wheel 3 is then inserted between the free ends of the side plates 5 and pivot pin 13 is slipped through the aligned openings in the trolley wheel and side plates and secured 75 in place by means of a cotter pin or other suitable means. Side plates 5 are provided at suitable locations, such as along their edges, with appropriate stop members 14 and 15, which serve to limit the amount of 80 rotation of the attachment about its pivot 11. In the construction shown this rotation may be as much as approximately 150°.

When moving forwardly as indicated by the solid arrow in Fig. 1, the parts will 85 occupy the relative positions shown in solid lines in this figure, which puts the wear plate 7 in contact with the trolley wire 16 and wheel 3 out of contact therewith, as shown most clearly in Fig. 3.

From the foregoing description it will be apparent that if the wear plate 7 becomes unduly worn from use the bolt 10 may be removed and then a new wear plate can be substituted for the one removed. Owing 90 to the peculiar shape of the parts 7 and 8 there will be substantially no looseness and relative movement of these parts when secured in position. Since the trunnions 11 are formed on the external faces of the 95 plates 5 the attachment cannot become loosened from the harp and drop out, the parts being held in position by means of the bolts 9 and 10 as is obvious. Also, since the pivot member 13 is secured to 100 one or both of the plates 5, the security of these plates within the harp 2 is rendered doubly sure. The shape of the attachment is such that when used in connection with a line provided with block signal mechanism the car may move either forwardly or backwardly and the trolley will work 110

with equal facility in either direction. When the car starts to back, as shown by the dotted arrow in Fig. 1, the parts turn on pivots 11 into the dotted line position shown in this figure with both trolley wheel and wear plate contacting the wire. When the car again starts to move forwardly, the attachment carrying wheel 3 will turn around its pivots 11 until the parts are again 10 in the relative positions shown in solid lines in Fig. 1.

The fact that this device can operate both forwardly and rearwardly in conjunction with block signal mechanism (as distinguished from prior devices of this type) is considered very important.

It is of course understood that the specific description of structure set forth above may be departed from without departing from 20 the spirit of my invention as set forth in this specification and the appended claims.

Having now described my invention, I claim:

1. A device of the class described comprising a shoe adapted to be inserted between the ordinary harp and trolley wheel of an electrically propelled vehicle, said shoe being weighted on one side of its pivot and light on the opposite side thereof and being adapted to pivotally support the trolley wheel in 30 the light side and when so supporting the trolley wheel the lighter side is heavier than the opposite side.

2. In a structure of the character described, a trolley harp, a shoe pivoted therein intermediate its ends, and a trolley wheel pivoted in one end of the shoe and capable of rotating freely in either direction, said end carrying the trolley wheel being heavier 40 than the opposite end and normally tending to hold said opposite end up in contact with the trolley wire.

3. In a structure of the character described, a shoe for insertion between the harp and wheel of a trolley pole, said shoe being pivoted in the harp bearings and having the wheel pivoted therein and comprising a pair of spaced side plates each carrying a pivot for the trolley wheel and provided with trunnions for the pivoting of the shoe in the harp, a block secured between the side plates and holding the same at a fixed 50 distance apart, and a removable and replaceable element normally sliding on the trolley wire when in use, located between the side plates.

4. In a structure of the character described, means to be inserted between a standard trolley wheel and harp, comprising 60 a grooved shoe provided with pivots mounted in the harp bearings, said shoe having bearings for the reception of the trolley wheel pivot, and a trolley wheel having its pivot mounted in said bearings, the moment of the weighted portion of the shoe about its

axis being less than that of the trolley wheel about said axis.

5. An attachment to be inserted between a standard trolley wheel and harp comprising a pair of complementary plates provided on their exterior faces with trunnions, one end of said attachment being provided with trolley wheel bearings and the opposite side being weighted to enable the attachment to be easily turned about its pivot. 75

6. In an attachment of the character described, a pair of side plates provided approximately centrally with outwardly extending trunnions, a shoe located between the side plates and to the opposite sides of 80 which the plates are secured, said shoe comprising two separable parts one of which constitutes a replaceable wear plate to engage the trolley wire in normal condition of use. 85

7. In an attachment of the character described, a pair of side plates provided approximately centrally with outwardly extending trunnions, a shoe located between the side plates and to the opposite sides of 90 which the plates are secured, said shoe comprising two separable parts one of which constitutes a replaceable wear plate to engage the trolley wire in normal condition of use, and the other of which normally remains fixed between the side plates. 95

8. In an attachment of the character described, a pair of side plates provided approximately centrally with outwardly extending trunnions, a combined weight and 100 shoe located between the side plates and to the opposite sides of which the plates are secured, said combined weight and shoe comprising two separable parts one of which constitutes a replaceable wear plate to engage the trolley wire in normal condition of use, and the other of which normally remains fixed between the side plates, said attachment having projections which normally serve as stop members to limit the amount 110 of rotation of the attachment about its pivots by engagement of said projections with the sides of the harp. 110

9. An attachment to be inserted between a standard trolley wheel and harp comprising 115 a pair of complementary plates provided on their exterior faces with trunnions, said attachment being provided with trolley wheel bearings and being constructed and arranged to enable the attachment to be 120 easily turned about its pivot, said attachment being grooved along one edge to receive a trolley wire and being adapted to operate in conjunction with block signal mechanism when running either forwardly 125 or backwardly.

10. A device of the character described comprising an attachment having lateral trunnions adapted to engage the usual trolley wheel bearing of a standard harp, said 130

attachment having a peripheral groove to receive the trolley wire and provided with spaced bearings of a size adapted to receive the standard pivot pin of the usual trolley wheel.

11. An attachment to be inserted between a standard trolley wheel and harp comprising means provided with trunnions to engage the harp to permit said means to shift relatively to said harp, said means having trolley wheel bearings and provided with a detachable wear plate to engage the trolley wire in the normal condition of use.

10 12. A device of the character described

comprising supporting means having lateral trunnions adapted to engage the trolley wheel bearing of a harp, said supporting means having a peripheral groove and provided with spaced bearings of a size adapted to receive the pivot pin of the standard size trolley wheel.

In witness whereof, I hereunto subscribe my name to this specification in the presence of two witnesses:

JAY F. O'NEAL.
